CLAIM

The ornamental design for a shoulder pack, as shown and described.

DESCRIPTION

FIG. 1 is a front, right, and top perspective view of a shoulder pack, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right, and top perspective view of a shoulder pack wherein the cover of shoulder pack is open.

FIG. 10 is another front, right, and top perspective view of a shoulder pack wherein the cover of shoulder pack is open.

FIG. 11 is a partial enlarged view of an area labeled 11 in FIG. 1 comprising a buckle; and,

FIG. 12 is a partial enlarged view of an area labeled 12 in FIG. 2 comprising a buckle.

The dash-dash broken lines depict portions of the shoulder pack that form no part of the claimed design. The long dash short dash broken lines in FIGS. 1, 2, 11, and 12 depict bounds of the enlargement taken from FIGS. 1 and 2 and form no part of the claimed design.
